UNITED STATES PATENT OFFICE.

WILLIAM J. ENSWORTH, OF ERIE, PENNSYLVANIA, ASSIGNOR OF ONE-FOURTH TO JOHN W. GALBRAITH, OF SAME PLACE.

CASH-REGISTER.

SPECIFICATION forming part of Letters Patent No. 591,748, dated October 12, 1897.

Application filed January 23, 1897. Serial No. 620,398. (No model.)

To all whom it may concern:

Be it known that I, WILLIAM J. ENSWORTH, of Erie, in the county of Erie and State of Pennsylvania, have invented a new and Improved Cash-Register, of which the following is a full, clear, and exact description.

This invention relates to an improvement in that class of cash-registers by which the amount of each sale is visually indicated and at the same time cast into an aggregate register of the sales, so that the machine will always indicate at its registering mechanism the amount of cash which should be in the drawer.

15 The invention consists in such peculiar features of construction and combination of parts as will be fully described hereinafter and defined in the claims.

Reference is to be had to the accompanying drawings, forming a part of this specification, in which similar characters of reference indicate corresponding parts in all the figures.

Figure 1 is a fragmentary plan of the invention, parts being shown in section. Fig. 2 is a front elevation with parts broken away to disclose the interior. Fig. 3 is a vertical longitudinal section, and Fig. 4 is a similar view showing the parts in different positions.

The casing or frame of the register has a bottom 5 with four vertical sides 6 and a sheet-metal top 7, shaped to conform with the mechanism within the casing. Slidable longitudinally on the bottom 5 is a cash-drawer 8, having an expansive spring 9 normally pressing against the rear wall 6 and serving to project the drawer forwardly when the drawer is released. A horizontal plate 11 is held within the casing and has its inner portion 12 separated from the outer portion and 30 pivotally connected thereto by a hinge 13. The movable plate 12 is capable of dropping downward when the drawer 8 is moved outward, as shown in Fig. 4. Pivoted on a rod 14, running transversely within the casing

45 and directly adjacent to the rear wall thereof, is a transversely-elongated shoe 15, projecting over the rear edge of the movable plate 12 and having rigidly connected therewith a catch 16, which extends downward through an opening in the rear stationary portion of the plate 11. The catch 16 is adapted to en-

ter an opening 17 in a plate 18, secured to the upper rear portion of the drawer 8. By these means the drawer is normally held within the casing against the tension of the spring 55 9. The rod 14 is located at the top of the rear portion of the stationary plate 11 and is pressed so as to throw the catch 16 downward by means of a spring 19. (Shown in Figs. 3 and 4.)

Mounted within the casing is a revoluble transverse shaft 20, located approximately midway the length of the casing and above the portion 12 of the plate 11. Fixed to the shaft 20 is a large wheel 21, the periphery of 60 which is provided with numerals divisible by five and running from "5" to "100." These numbers represent cents in the record kept by the machine. Fixed to the shaft 20 is a lug 22, adapted to engage with teeth formed on 65 the periphery of a wheel 23, mounted on a counter-shaft 24, held in the casing. The periphery of the wheel 23 is also provided with numbers running consecutively from "1" to "100," and representing dollars in the record 70 kept by the machine. A single revolution of the shaft 20 advances the wheel twenty-three one-hundredths of a revolution by the engagement of the lug or projection 22 with the teeth on the wheel 23. Fixed to the shaft 20 75 is a pinion 24^a, having a comparatively large number of small teeth. Adjacent to the pinion 24^a is a pinion 25, fixed on the shaft 20 and having a diameter greater than that of the pinion 24 and also having larger and less 80 numerous teeth than the pinion 24^a. A still larger pinion 26 is fixed to the shaft 20 adjacent to the pinion 25, and a pinion 27 is fixed adjacent to the pinion 26, which pinion 27 is also larger than the pinions previously described. The remainder of the shaft 20 is occupied by a transversely-elongated drum 85 28 with teeth and diameter coextensive with the teeth and diameter of the pinion 27.

Carried longitudinally on the upper side 90 of the movable plate 12 are a series of dovetailed cleats 29, which form parallel guide-ways wherein the rack-bars 35, 30, 31, 32, 33, and 34 respectively run. The rack-bars 35 all mesh with the drum 28, and the number 100 of teeth on each rack-bar 35 is gradually diminished from the rack-bar which is far-

thest to the left. The rack-bar 35 farthest to the left, which has the greatest number of teeth, stands for "95 cents," which is nearly a complete revolution of the drum 28. 5 The immediately-adjacent rack-bar 35 is capable of registering "90 cents," and therefore causes a revolution of the drum 28 slightly less than a revolution brought about by the movement of the rack-bar farthest to 10 the left, so the diminution runs until the rack-bar farthest to the right and having the least number of teeth stands for "5 cents" and turns the drum 28 one-twentieth of a revolution. The rack-bar 30 meshes with the 15 pinion 27 and has a single number of teeth to turn the shaft 20 a single complete revolution. The rack-bar 30 stands, therefore, for "\$1." The rack-bar 31 meshes with the pinion 26 and has a sufficient number of teeth 20 to turn the shaft 20 two complete revolutions. The rack-bar 31 stands, therefore, for "\$2." The rack-bar 32 meshes with the pinion 25 and turns the shaft 20 three revolutions and stands for "\$3," and the rack-bar 33 meshes 25 with the pinion 24 and turns the shaft 20 four revolutions and stands for "\$4." The rack-bars 34, according to the specific arrangement here illustrated, are superfluous, but they may be provided with teeth increased 30 in number over those on the rack-bars 33, so as to register "\$5" and "\$6," if desired. Each rack-bar has an elevation sufficient to cause its teeth to properly mesh with the respective pinions or drum, as may be seen by 35 reference to Fig. 2. The rack-bars 35 (shown outside of the cover-plate 7 in this view) are sectioned on a line forward of the rack-bars shown inside of the cover-plate 7. All of the rack-bars at points normally outside of the 40 cover-plates 7 may be made hollow, as shown at the right in Fig. 2, for convenience in manufacturing. Located within a cavity in each of the rack-bars is a retractile spring 36. One end of each spring 36 is fixed to its respective 45 rack-bar, and the other end of each spring is fixed to the forward portion of the plate 11. These springs serve to hold the rack-bars in a forwardmost position, as shown by full lines in Fig. 4. When the rack-bars are moved 50 rearward to actuate the shaft 20, they move against the tension of the springs 36. As the rack-bars approach the limit of their rearward movement the inclined rear ends of the rack-bars, as shown in Fig. 4, engage with the shoe 15 and lift the same, as the dotted lines in Fig. 4 show, and this releases the drawer 8 by moving the catch 16 upward. Upon this operation the spring 9 asserts 55 itself to project the drawer forwardly, as also shown in Fig. 4. The movable plate 12 is now without support, and the action of the spring 36 on that rack-bar which has been moved rearward will cause the plate 12 to drop to the position shown by full lines in 60 Fig. 4. The plate 12 moving downward carries with it the rack-bars, which are consequently disengaged from their respective pin-

ions and drums, and the rack-bar which has been pushed rearward is permitted to return without engagement with the corresponding 70 pinion or drum on the shaft 20. When therefore a sale is made, the appropriate rack-bar is pushed inward, the amount of the sale is cast into the aggregate record kept by the wheels 21 and 23, and the drawer 8 is pushed 75 forward to permit the deposit of the cash therein. Figs. 3 and 4 illustrate a spring-pressed pawl 37, which is fixed to the rear wall of the casing and projects forwardly to bear down upon the drum 28 and prevent 80 loose movement thereof. A similar spring 38 (shown in Fig. 1) bears upon the teeth of the wheel 23 to prevent the loose revolution of this wheel.

The top 7 of the casing is curved at an intermediate point to conform to the wheel 21, and at a point just above this curve the casing is provided with openings 39, through which the operator may observe sale-indicating devices, which will now be described. A 85 shaft 40 extends transversely above the wheel 21 and adjacent to the openings 39. Fixed to this shaft 40 is a series of right-angled plates 41, on the adjacent faces of each of which are printed numbers respectively corresponding to the rack-bars. Each rack-bar is provided at the point above its spring 36 with a rising-and-falling cam 42. These cams 42 are arranged to engage the lower bar 43 of a frame 44, slidable diagonally in supports 45 and 46. When one of the rack-bars is pushed rearward, its cam 42 engages the lower bar 43 of the frame 44 and causes the frame to move upward. Should any of the plates 41 be in the position shown by dotted lines in Fig. 3 and by full lines in Fig. 4, the upper bar 47 of the frame 44 will engage with such plate 41 and swing the same to the position shown by full lines in Fig. 3 and by dotted lines in Fig. 4. When in these positions, 105 no number is visible through the openings 39. Bars 48, one for each rack-bar, slide independently in the support 45 and in an additional support 49. Immediately after the cam on that rack-bar which has been operated 110 passes the bar 43 the frame 44 will return to its lower position and the cam will then engage its corresponding bar 48 and push this bar up independently of the other bar 48, so that that angle-plate 41 which is actuated by 115 the bar 48 that has been moved will be thrown to the position shown by full lines in Fig. 4 and by dotted lines in Fig. 3, which position is such that a number will appear through the corresponding opening 39, which number will 120 correspond with the amount for which the rack-bar that has been operated stands. When the rack-bar returns, its cam 42 again engages the frame 44 and operates the same to throw that plate 41 which has just been 125 operated into a position at which it will show no number through the corresponding opening 39.

By the mechanism just described I have

- provided a register which has a cash-drawer to receive the cash and which casts into an aggregate register all sales that are made. The cash-register also displays the amount of 5 each sale individually at the moment of its register. The form shown is adapted only for the register of sums divisible by five. It is obvious, however, that this can be changed to make any number registerable.
- 10 In using the invention the operator pushes inward the rack - bar bearing the number which corresponds with the sale the operator has made and permits the drawer 8 to be shoved forward by its spring 9. The cash 15 may now be deposited within the drawer 8 and the drawer then returned. As the drawer is moved forward the plate 12 drops to permit the operated rack-bar to return, and immediately before its return the registering 20 mechanism will have been moved to cast the sale into the sum of all of the sales.
- Having thus described my invention, I claim as new and desire to secure by Letters Patent—
- 25 1. The combination with a casing, of a drawer slideable therein, a movable plate normally sustained by the drawer, a rack - bar sliding on and carried by the plate, a gear engaged by the rack-bar and from which the 30 rack-bar is moved by the movement of the plate carrying the rack-bar, and registering mechanism in connection with the gear, substantially as described.
- 35 2. The combination with a casing, of a drawer slideable therein, a plate normally sustained by the drawer, a rack-bar carried on and moving with the plate, and mechanism engaged and operated by the rack-bar, and from engagement with which the rack - bar 40 moves when the plate carrying the rack-bar is moved, substantially as described.
- 45 3. The combination with a casing, of a drawer slideable therein, a movable plate sustained by the drawer, a rack-bar sliding on and supported by the plate, a gear with which the rack-bar engages and from which the rack-bar moves when the plate is dropped, and registering mechanism in connection with the gear, substantially as described.
- 50 4. The combination with a casing, of a drawer movable therein, a movable plate normally sustained by the drawer, a catch holding the drawer in position to sustain the plate, a rack-bar sliding on and carried by the plate 55 and capable of releasing the catch, and registering mechanism in connection with and operated by the rack-bar and from which the rack - bar moves when the movable plate moves, substantially as described.
- 60 5. The combination with a casing, of a drawer movable therein, a catch holding the drawer, a movable plate normally sustained by the drawer, a rack-bar sliding on and supported by the movable plate and capable of 65 releasing the catch as the rack-bar is moved, and registering mechanism operated by the rack-bar and from which the rack-bar moves

when the movable plate moves, substantially as described.

6. The combination with a casing, of a drawer movable therein, a stationary plate held above the drawer, a movable plate inclosed by the stationary plate and normally sustained by the drawer, a rack-bar movable on and held by the movable plate and capable of releasing the catch upon the movement of the rack-bar, and registering mechanism with which the rack - bar is connected and from which the rack-bar moves when the movable plate moves, substantially as described. 75

7. The combination with a casing, of an angle sign-plate pivoted therein on an axis co-extensive with the angle of the sign-plate, two parts respectively engaging the sign-plate on 85 opposite sides of the pivot thereof, and a part movable within the casing and engaging each of the first-named movable parts to rock the sign-plate back and forth, substantially as described. 90

8. The combination with a casing, of a sign-plate pivoted therein, two parts respectively engaging the sign-plate on opposite sides of its pivot, and a part movable within the casing and engaging the two first-named movable 95 parts to rock the sign-plate back and forth, substantially as described.

9. The combination with a casing having a pivoted sign-plate therein, two parts respectively engaging the sign-plate on opposite 100 sides of its pivot, and an additional part movable within the casing and having a rise-and-fall cam capable of engaging each of the first-named movable parts to rock the sign-plate back and forth, substantially as described. 105

10. The combination with a casing, of a member slideable therein, a rack-bar supported by the said slideable member, and mechanism engaged by the rack-bar when the rack-bar is supported by the said slideable member, 110 the slideable member being movable to drop the rack-bar.

11. The combination with a casing, of a slideable member contained therein, a movable plate normally sustained by the slideable member, a rack - bar operative on the movable plate, a gear with which the rack-bar engages and from which the rack-bar moves when the plate is dropped, and registering mechanism coacting with the gear. 115

12. The combination of a pivoted member, two parts reciprocal longitudinally toward and from the member and respectively on opposite sides of the pivot thereof, and a reciprocal part having a cam movable to successively exert endwise pressure on said two moving parts whereby to alternately operate the same. 120

13. The combination of a shaft, a series of differential gears thereon, a series of rack-bars respectively engaging the gears and turning the shaft various degrees of revolution, and registering mechanism actuated from the shaft. 130

14. The combination of a shaft, a bed-plate parallel with the shaft, a series of gears of differential diameter fixed on the shaft, and a series of rack-bars respectively meshing with the gears and having heights varying in accord with the size of the gears.
15. The combination with a casing, of a drawer slideable therein, a vertically-movable plate located above the drawer and supported by the drawer, a rack-bar sliding and carried on the plate, and a gear engaged by the rack-bar when the drawer is located beneath the gear, the drawer when in said position serving to raise the plate.
16. The combination of a plurality of gears, a rigid plate located beneath the gears, the plate having a plurality of parallel guides, rack-bars respectively reciprocal in the guides and respectively engaging the gears, and a drawer located beneath the plate and normally supporting the plate, the drawer being capable of moving from beneath the plate to allow the plate to drop and disengage the racks and the gears.
17. The combination of a series of differential gears turning on an axis common to all, a separately-operative gear for each of said differential gears and serving to impart movement thereto, and a registering device in connection with the axis of said differential gears and having movement imparted to it from the movement of the differential gears and proportionately inversely to the size of said gears.
18. The combination of a shaft, a series of differential gears fixed thereon, one of said gears being elongated, a plurality of operating-gears all meshed with the elongated gear and imparting thereto various degrees of movement, additional gears respectively meshed with the remaining of the differential gears, and a registering mechanism operated from the differential gears.
19. The combination of a series of differential gears, one of which is elongated with its axis, a series of movement-imparting devices coacting with said gear and serving to impart varying degrees of movement thereto, additional movement-imparting devices respectively coacting with the remaining differential gears, and a registering device operated from said differential gears.
20. In a cash-register, a registering device, a rotatable shaft geared thereto, the diameter of the two portions of said shaft varying, and a plurality of toothed key-rods geared to said toothed shaft.
